UNITED STATES PATENT OFFICE.

JOHN L. ROACH, OF CHILDRESS, TEXAS.

DRIVING BOX FOR LOCOMOTIVES.

Application filed May 13, 1924. Serial No. 713,016.

To all whom it may concern:

Be it known that I, JOHN L. ROACH, a citizen of the United States, residing in the city and county of Childress and State of Texas, have invented certain new and useful Improvements in Driving Boxes for Locomotives, of which the following is a specification.

This invention relates to a driving box for locomotives and has for its object to provide a box of such class, in a manner as hereinafter set forth, with means whereby the wear resisting liners will extend below the horizontal center line of the journal or axle, thus increasing the wearing surface and eliminating the tendency to lift the driving box on the journal when in operation.

A further object of the invention is to provide, in a manner as hereinafter set forth, a driving box having its body portion formed of two sections permitting of making adjustments for wear between the journal and driving box liners by adjusting the pedestal wedge, thus eliminating the necessity of removing the driving wheels for repair.

A further object of the invention is to provide, in a manner as hereinafter set forth, a driving box so constructed whereby the liability of heating the journal and the loosening of the driving box liners is reduced to a minimum, due to the fact that the pressure between the journal and the liners can be relieved by proper adjustment of the pedestal wedge.

Further objects of the invention are to provide, in a manner as hereinafter set forth, a sectional driving box for locomotives, which is simple in its construction and arrangement, strong, compact, durable, thoroughly efficient in its use, readily installed, and comparatively inexpensive.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference

characters denote corresponding parts throughout the several views:—

Figure 1 is a sectional elevation of a driving box in accordance with this invention.

Figure 2 is a top plan view thereof.

Figure 3 is a longitudinal sectional view of the driving spring saddle support.

Figure 4 is an end view of the support.

Figure 5 is a perspective view of a closure strip employed in connection with the liners.

The body portion of the driving box, which is substantially of inverted U-shape is indicated generally at 1, and is formed with two oppositely disposed inverted substantially L-shaped sections 2, 3, of like construction and having the upper portions extending towards and in close proximity to each other.

Each of said sections has a portion of its inner face of arcuate curvature to provide a seat 4, for a liner 5. The seat 4 extends from a point in close proximity to the inner upper edge of the section and terminates at a point removed from the lower end thereof, but below the horizontal center thereof. The length of each of the seats is such as to extend below the horizontal center line of the journal 6, indicated in dotted lines in Figure 1.

The inner terminus of the upper portion of each of said sections has projecting from the inner face thereof, a transversely extending vertically disposed rib 7, having its outer face flush with the inner edge of the upper portion of the section. The upper end of the seat 4 merges into the inner side of the rib 7. At the lower terminus of the seat 4 each section is provided with an inwardly projecting and upwardly inclined transversely extending lug 8.

The liner 5, which is segmental in contour, is of a length to extend from the inner edge of the upper portion of the section to the lug 8, and the liner is cut away, as at 9, to seat against the lower and inner side edge of the rib 7. The upper edge of the liner 5 is flush with the outer side edge of the rib 7. The liner 5 is mounted against the seat 4, abuts against the inner side edge of the rib 7 and is supported on the upper side of the lug 8. The liner 5 gradually decreases in thickness from the cut-out portion 9 to its lower edge, and said liner 5 at its lower edge is of a width to slightly project beyond the lug 8.

The upper edge of the liner 5 is formed with a transversely extending groove, and the grooves of said liners oppose each other when the liners 5 are mounted in the sections 5 2, 3, of the box 1.

Each of the sections is formed with side flanges 11 and 12, which project upwardly and laterally but terminate at a point removed from the lower end of the section.

10 The upper face of each section between the flanges 11 and 12, is of arcuate curvature, as indicated at 13; and the upper face of one section is a continuation of the arc of the upper face of the other section.

15 The upper face of each section of the box 1 is provided with a pair of transversely extending spaced webs 14 and 15. The web 15 is apertured, as at 16 and has its outer face flush with the vertical portion of the 20 section. The web 14 is spaced a substantial distance from the web 15.

The webs 14 of the sections, when these latter are arranged in coacting relation to set up the body portion of the box, provide in 25 connection with the upper faces of the sections, a pocket 17. The inner faces of the flanges 11 and 12, inwardly with respect to the webs 14, are cut out, as at 18, thus forming the ends of the pocket 17. The side walls 30 of the pocket 17 are provided by the webs 14 and the end walls by the flanges 11 and 12, as clearly shown in Figure 2.

The pocket 17 is provided for the reception of a support for the driving spring 35 saddle, and said support consists of a rectangular block 19, having its lower face 20 conforming in contour to the shape of the bottom of the pocket 17. The block 19 is of less height than the height of the webs 40 14, and said block 19 at each end thereof is grooved, as at 21, and which in connection with the flanges 11 and 12 provides the support 19 with transversely extending cavities having each end positioned in proximity to 45 a side of the block and which are adapted to receive the driving spring saddle.

When the sections 2, 3, are in opposed relation, the space 22 between the opposed inner ends of the upper portions of said sections, is closed by a strip 23, which is mounted in the opposed grooves 10 of the liners 5, and said strip prevents lubricant from being carried to the top of the driving box.

It is to be understood, however, that the 55 driving box will be fitted with pedestal shoes and wedges, as well as with a driving box cellar, such parts are not shown as they form no part of the invention.

A driving box constructed in the manner 60 as stated, that is having its body portion formed of two sections, permits of extending wear resisting liners below the horizontal center line of the journal, thus increasing wearing surface and eliminating the tendency to lift the driving box on the journal

when in operation. The sectional construction also permits of making adjustments for wear between the journal and the driving box liners by adjusting the pedestal wedge, thus eliminating the necessity of removing 70 the driving wheels for repairs. A box constructed in a manner as stated furthermore reduces liability of the heating of the journal and the loosening of the liners in the box by relieving pressure between the journal 75 and the liners and which can be accomplished by proper adjustment of the pedestal wedge.

It is thought that the many advantages of a driving box, in accordance with this invention, can be readily understood, and although the preferred embodiment of the invention is as illustrated and described, yet changes in the details of construction can be had which will fall within the scope of 80 the invention as claimed.

What I claim is:—

1. A driving box for locomotives comprising a body portion formed of a pair of oppositely disposed complementary sections 90 each having its inner face provided with a longitudinally disposed rib and lug spaced from each other, the outer side of each of said ribs forming a continuation of the inner end edge of a section said lugs arranged below the horizontal center line of a journal, and oppositely disposed liners seated on said lugs and abutting against the inner sides of and further overlapping said ribs, the upper end edges of said liners opposing each other and flush throughout with the inner end edges of said sections. 95

2. A driving box for locomotives comprising a body portion formed of a pair

105 of oppositely disposed complementary sections

each having its inner face provided with a longitudinally disposed rib and lug spaced from each other, the outer side of each of

said ribs forming a continuation of the inner end edge of a section said lugs arranged

110 below the horizontal center line of a journal, oppositely disposed liners seated on said

lugs and abutting against the inner sides of

and further overlapping said ribs, the upper

end edges of said liners opposing each other

and flush throughout with the inner end

edges of said sections, and a bridging strip

common to the opposed upper end edges of

115 said liners and seated therein throughout.

3. A driving box for locomotives comprising an inverted U-shaped body portion

120 formed of a pair of oppositely extending

complementary sections each having its inner

face formed with a depending vertically

125 disposed longitudinal rib and an upwardly

inclined lug spaced from the rib, the outer

side of each of said ribs forming a continuation

120 of the inner end edge of a section said lugs positioned below the longitudinal

center line of a journal, and oppositely dis-

posed liners seated on said lugs and abutting against the inner sides of and further overlapping said ribs, the upper end edges of said liners opposing each other and flush throughout with the inner end edges of said sections.

4. A driving box for locomotives comprising an inverted U-shaped body portion formed of a pair of oppositely extending complementary sections each having its inner face formed with a depending vertically disposed longitudinal rib and an upwardly inclined lug spaced from the rib, the outer side of each of said ribs forming a continuation of the inner end edge of a section said lugs positioned below the longitudinal center line of a journal, and oppositely disposed liners seated on said lugs and abutting against the inner sides of and further overlapping said ribs, the upper end edges of said liners opposing each other and flush throughout with the inner end edges of said sections, said upper edges having inwardly projecting opposed lengthwise extending grooves, and a thick, flat bridging strip common to said liners and seated in said grooves.

5. A driving box for locomotives comprising a body portion formed of a pair of oppositely disposed independent complementary sections, each of said sections provided on its top with a pair of spaced vertical flanges and a vertical web spaced from the inner end of and integral with the inner side of said flanges, said sections in connection with the webs and flanges thereof forming a pocket transversely of the top of the body portion for removably receiving a spring saddle support.

6. A driving box for locomotives comprising a body portion formed of a pair of oppositely disposed independent complementary sections, each of said sections provided on its top with a pair of spaced vertical flanges and a vertical web spaced from the inner end of and integral with the inner side of said flanges, said sections in connection with the webs and flanges thereof providing a pocket extending transversely of the top of said body portion, and a removable spring saddle support mounted in said pocket.

7. A driving box for locomotives comprising a body portion formed of a pair of oppositely disposed independent complementary sections, each of said sections provided on its top with a pair of spaced vertical flanges and a vertical web spaced from the inner end of and integral with the inner

side of said flanges, said sections in connection with the webs and flanges thereof forming a pocket transversely of the top of the body portion for removably receiving a spring saddle support, said webs of less height than the height of said flanges.

8. A driving box for locomotives comprising a body portion formed of a pair of oppositely disposed independent complementary sections, each of said sections provided on its top with a pair of spaced vertical flanges and a vertical web spaced from the inner end of and integral with the inner side of said flanges, said sections in connection with the webs and flanges thereof providing a pocket extending transversely of the top of said body portion, and a removable spring saddle support mounted in said pocket and of less height than the depth of the pocket.

9. A driving box for locomotives comprising an inverted U-shaped body portion formed of a pair of oppositely disposed independent complementary sections, each of said sections provided with a pair of spaced flanges extending throughout the outer side thereof and a vertical web spaced from the inner ends of and integral with the inner sides of said flanges, said webs, flanges and the top of said sections providing a transversely extending pocket for removably receiving a spring saddle support, and each of said sections furthermore provided at its top with an apertured web integral with the inner sides of the flanges and spaced from the first mentioned web.

10. A driving box for locomotives comprising an inverted U-shaped body portion formed of a pair of oppositely disposed independent complementary sections, each of said sections provided with a pair of spaced flanges extending throughout the outer side thereof and a vertical web spaced from the inner ends of and integral with the inner sides of said flanges, said webs, flanges and the top of said sections providing a transversely extending pocket for removably receiving a spring saddle support, and each of said sections furthermore provided at its top with an apertured web integral with the inner sides of the flanges and spaced from the first mentioned web, that part of said flanges inwardly with respect to the webs cut out to form shoulders, the inner faces of said webs flush with said shoulders.

In testimony whereof, I affix my signature hereto.

JOHN L. ROACH.
